DUPLEX VARIABLE RESISTOR

Shunzo Oka, Hirakata, and Akitoshi Miyashita, Suita, Japan, assignors to Matsushita Electric Industrial Co., Ltd., Osaka, Japan

Filed July 2, 1971, Ser. No. 159,587

Term of patent 14 years

Int. Cl. D13—03

U.S. Cl. D26—1 D

FIG. 1

FIG. 2

FIG. 3

FIG. 4

FIG. 1 is a top, rear perspective view of a duplex variable resistor showing our new design;

FIG. 2 is a top, front perspective view thereof;

FIG. 3 is a bottom, rear perspective view thereof; and

FIG. 4 is a front, perspective view thereof, with the mounting plate oriented vertically.

We claim:

The ornamental design for a duplex variable resistor, as shown and described.
